UNITED STATES PATENT OFFICE.

GEORGE J. KITZING, OF INDIANAPOLIS, INDIANA.

COMBINED SPRINKLER AND NOZZLE.

SPECIFICATION forming part of Letters Patent No. 619,189, dated February 7, 1899.

Application filed October 16, 1897. Serial No. 655,248. (No model.)

To all whom it may concern:

Be it known that I, GEORGE J. KITZING, a citizen of the United States, residing at Indianapolis, in the county of Marion and State of Indiana, have invented certain new and useful Improvements in a Combined Sprinkler and Nozzle; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to the class of devices that are designed to be used in connection with garden or yard hose for the purpose of sprinkling water upon lawns or buildings; and it consists in a certain novel device attached to a nozzle whereby the stream is sprayed horizontally and in a novel manner and by which the sprinkler may be converted at will into a nozzle for discharging a solid stream of water; and it further consists in a stand therefor of novel construction and in the parts and combination thereof forming the complete sprinkler, as will be more fully described hereinafter and claimed.

25 Lawn-sprinklers as heretofore constructed have serious defects in that they elevate the water to such an extent that it is caught by the winds and blown away from the parts intended to be sprinkled and often onto passing pedestrians or into house windows or doors, rendering them highly objectionable; and it 35 is my object to eliminate these evils and provide means whereby water may be sprinkled at any desired point more positively and the device transferred readily from one point to another without the necessity of going a distance to shut off the water-supply in order to move it without becoming wet by the spray.

40 A further object is to provide such a sprinkler as may be quickly changed without using tools into a plain nozzle, by which water may be thrown in a solid stream into vases or when washing windows or porches, &c.

45 These objects are attained in my invention, which is furthermore simple in design, 50 cheaply constructed, and efficient and durable in use.

Referring to the drawings, Figure 1 repre-

sents a side elevation of my sprinkler complete upon its stand; Fig. 2, a front elevation thereof; Fig. 3, a plan view of the stand; Fig. 55 4, a plan view of the nozzle and sprinkling device detached from the stand; Fig. 5, a central vertical sectional view of the nozzle and sprinkling device, showing the latter also in dotted lines as swung around at the side 60 of the nozzle when using the latter for delivering a solid stream; Fig. 6, a central vertical sectional view, and Fig. 7 a front view, of a modified form of stand.

In the drawings, A designates the nozzle, 65 B the sprinkler, and C and D stands therefor.

In constructing my devices I make a cylindrical nozzle, preferably of cast-brass, having in its base screw-threads *m*, adapted to engage the male half of a hose-coupling, and a 70 central duct restricted at its upper end and terminating in the orifice *h* of suitable size. Extending from one side is an arm *a*, preferably integral and approximately at a right angle to the line of the duct, the latter being 75 considered as vertical, and near the end of the arm is a vertical hole having screw-threads therein, although the threads may be omitted if two thumb-nuts are used on the standard 80 *b*, which is preferably a cylindrical rod provided with screw-threads for a short distance from its lower end, which is inserted in the hole, and a thumb-nut *d* is screwed onto it either above or below the arm to lock the standard in any position in which it may be 85 set. The upper end of the standard *b* is flattened and turned over to form a horizontal arm *i*, to which a circular metallic disk-shaped sprinkler *B* is secured by a rivet *e* or screw-bolt. The sprinkler has a greater diameter 90 than the orifice and has a flat or plane surface presented toward the orifice of the nozzle at a right angle to its duct and centrally at a suitable distance above the orifice.

The base *C* is designed to be made cheaply 95 when large sizes are desired and which may be readily repaired by ordinary blacksmiths in rural districts should it be accidentally broken, and it consists in a frame *E* and two side pieces *F* *F*, preferably forgings, the latter in the shape of double-ended runners, each composed of a flat bar of wrought-iron bent up near the ends to form the rounded corners *u* and at the ends turned over to form hori-

zontal lips P, through which a bolt-hole is drilled or punched. The frame is of the "spider" form, having four arms or legs inclined downward and having horizontal ends 5 N, in which is a bolt-hole to receive a screw-bolt Q, by which the frame and runners are connected detachably. The center of the frame has a vertical hole through a "boss" G I and provided with pipe-threads. The pipe 10 H of suitable length has pipe-threads at its lower end and is attached to the end G of the boss and its upper end has "hose-threads" and receives the nozzle. A pipe-nipple J is screwed into the end I of the boss, and at its 15 lower end is an elbow K, to which is screwed a nipple L, having a hose-nut M, to which a garden-hose may be connected. The stand D is adapted for ordinary sizes for lawns and is preferably made of malleable iron in a single 20 piece, having the central boss S provided with pipe-threads n, to which the pipe H may be attached, and a spreading, frame v terminating in runners R, having rounded ends W. An integral elbow T has a socket U provided 25 with pipe-threads, to which is screwed the nipple L, having the coupling-nut.

Minor changes in the details of construction may be made, as it is not essential that the sprinkler B shall be mounted exactly as 30 shown; but any other arrangement is permissible so that it is situated adjustably above the orifice of the nozzle and preferably arranged so that it may be swung away to clear the stream from the nozzle. It is of great ad- 35 vantage to use the stand having runners provided with rounded ends, particularly at the front, so that when it is desired to change the position of the sprinkler it is only necessary to draw it along the ground by pulling the 40 hose to which it is attached in any desired direction, the rounded ends of the runners causing it to slide freely. The advantage in the sprinkler lies in the peculiar shape and arrangement of the disk above the nozzle, so 45 that as the water escapes it is spread out horizontally with force in all directions and is atomized, falling in a spray without rising and being blown about by winds. When it is desired to use the plain nozzle, it may be de- 50 tached from the pipe H and connected to a hose, and the sprinkler B is swung to one side by first loosening the thumb-nut and then tightening it to secure the standard in its altered position.

55 I am aware that both concave and convex disks have been applied to nozzles to cause a spray and that neither possesses the advantages nor produces the desired results, as does my invention, as I have found that especially 60 in sprinkling large areas, as parks, the flat surface exposed to the stream produces the best result.

Having thus described my invention, what I claim, and desire to secure by Letters Patent, is—

1. In a lawn-sprinkler, the combination of the stand, the nozzle having the projecting

arm provided with the threaded hole at the outer end thereof, the standard secured in said threaded hole, whereby the length of the 70 standard is graduated, the thumb-nut to bind said standard, the horizontal arm on said standard, and the disk rigidly secured to said horizontal arm, said disk having a flat or plane surface presented toward the orifice of 75 said nozzle and adapted to cause water discharged therefrom to be spread out and sprayed horizontally in all directions radially from the center, substantially as and for the purposes shown and described. 80

2. In a combined lawn-sprinkler and nozzle, the combination of the nozzle having a base provided with screw-threads and having an unobstructed tapering cylindrical bore restricted at the discharging-orifice thereof, 85 the projecting horizontally-disposed arm attached rigidly to said nozzle and having the standard secured adjustably at the center end thereof and provided with the horizontal arm, and the disk rigidly secured to the horizontal arm of the standard and having a flat or plane surface presented toward the orifice of 90 said nozzle and adapted to cause water discharged therefrom to be spread out and sprayed in all directions radially and horizontally to said bore, substantially as and for the purposes set forth. 95

3. In a combined lawn-sprinkler and nozzle, the combination of the nozzle having a base provided with screw-threads and having an unobstructed tapering cylindrical bore restricted at the discharging-orifice, the projecting horizontal arm attached to said nozzle and provided with the threaded hole at the free end thereof, the standard having the horizontal arm and provided at its lower end with screw-threads engaging said threaded hole, the locking thumb-nut on said threaded lower end, and the disk secured rigidly to the horizontal arm of said standard, substantially as shown 100 and described, for the purposes set forth. 105

4. In a combined lawn-sprinkler and nozzle, the combination of the stand, the nozzle having the cylindrical bore restricted at the discharge-orifice thereof and detachably 110 mounted upon the stand, the arm extending laterally from said nozzle and having the screw-threaded hole at the extremity thereof, the standard having the flattened horizontal arm and provided at its lower end with screw-threads engaging said screw-threaded hole, the thumb-nut on said lower end and bearing against said lateral arm whereby said stand- 115 ard is secured adjustably, and the disk rigidly secured to said flattened horizontal arm, 120 substantially as shown and described. 125

5. In a combined lawn-sprinkler and nozzle, the combination of the stand, the detachable nozzle mounted vertically upon the stand and provided with the laterally-projecting 130 arm having the screw-threaded hole at the outer end thereof, the standard having the flattened horizontal arm and provided with the screw-threaded lower end engaging said

threaded hole whereby the said standard may be adjusted vertically, the thumb-nut on said threaded end whereby said standard is locked rigidly to said projecting arm, and the circular disk rigidly secured to said flattened arm, substantially as shown and described, for the purposes set forth.

6. In a lawn-sprinkler, the combination of the stand comprising the frame having the 10 detachably-connected runners and having the bosses at the center thereof, the pipe-nipple connected to the lower one of said bosses, the elbow connected to said nipple, the pipe connected to said elbow and having the hose-cou-

pling at the outer end thereof, the pipe-nipple 15 connected to the upper one of said bosses, the nozzle connected to said last-mentioned nipple and provided with the lateral arm, the standard adjustable on the arm, and the flat disk B rigid on said standard, substantially 20 as and for the purposes shown and described.

In testimony whereof I affix my signature in presence of two witnesses.

GEORGE J. KITZING.

Correction in Letters Patent No. 619,189.

It is hereby certified that in Letters Patent No. 619,189, granted February 7, 1899, upon the application of George J. Kitzing, of Indianapolis, Indiana, for an improvement in "A Combined Sprinkler and Nozzle," an error appears in the printed specification requiring correction, as follows; In line 88, page 2, the word "center" should read *outer*; and that the said Letters Patent should be read with this correction therein that the same may conform to the record of the case in the Patent Office.

Signed, countersigned, and sealed this 7th day of March, A. D., 1899.
